UNITED STATES PATENT OFFICE.

SMITH MADISON JOHNSON, OF MIDDLEFIELD, OHIO.

APPARATUS FOR FASTENING PAIL COVERS.

Application filed August 5, 1926. Serial No. 127,370.

This invention relates to improvements in apparatus for fastening pail covers, an object being to provide a movable mounting for the crimping mechanism, permitting 5 swinging such mechanism to one side and the placing of the pail upon the platform in the natural manner prior to again swinging the mechanism into operative position over the cover.

10 Other objects and advantages will appear in the following specification, reference being had to the accompanying drawings, in which

15 Figure 1 is a side elevation of the improved apparatus.

Figure 2 is a plan view.

Figure 3 is a detail sectional view taken on the line 3—3 of Figure 2.

This invention is an improvement on the 20 apparatus for fastening steel pail tops disclosed in my Patent 1,443,264 of January 23, 1923 to which, and also my Patent 1,459,469 of June 19, 1923, reference may be made to the details of the crimping mechanism. This mechanism will bear brief 25 description here so that the purpose of the improvement may readily be understood.

The crimping mechanism comprises a 30 cover crimping head comprising a base plate 1 with a standard 2 in the middle. A plurality of arms 9 are formed with crimping jaws 10 at one side of the pivotal mounting at 11 upon brackets 12 of the base plate, the other side of the arms being connected 35 with rods 6, the upper ends of which are joined with lugs 7 of a circular flange 5.

Pins 16 extending upwardly from a ring 40 17 pass through suitable guiding elements 18 upon the base plate 1, and carry springs 19 which tend to hold the base plate 1 in a predetermined position in respect to the lugs 13 when the mechanism is set in the operative position upon the cover C of the pail P. Downward movement of the circular flange 45 5 upon the standard 2 will rock the arms 9 to perform a crimping operation upon the lugs 13.

It is the purpose of the present invention 50 to make it possible to handle and operate the foregoing crimping mechanism, or closing head as it is sometimes called, to better advantage. The resulting movable mounting comprises the following structure: A platform 20 has a rigid standard 21 at one 55 end provided with a set collar 22 upon which the sleeve at one end of the arm 23 form-

ing a supporting and guiding frame for the crimping head, are swivelled for transverse swinging movement of the arm with its crimping head. A second set collar 24 near the top of the rigid standard holds the frame 23 down in place. A hook 25, pivotally mounted at 26 upon the set collar 24 may be swung over into engaging position with the top of the frame 23 to keep the latter from 60 swinging when in the operative position, and when desiring to move the apparatus from place to place upon the floor.

For the latter purpose the platform 20 has a pair of side wheels 27 near one extremity and a pair of casters 28 near the other. The reader may understand that if the frame 23 were permitted to swing free upon the standard 21, movement of the apparatus over the floor, would be difficult 70 75 and inconvenient, but by bringing the hook 25 over into engaging position, as stated, the frame is held in position and the apparatus can readily be transported. The frame 23 is of bracket formation. The free 80 extremity thereof has a boss 29 in which the standard 2 of the crimping mechanism is slidable. The boss has a shoulder 30 with which a latch 31 is engageable. This latch is pivotally mounted at 32 (Fig. 3) between 85 the side bars 33 of a handle 34. A rod 35 connects the latch with a pivoted member 36 upon the handle 34, depression of the latter swinging the latch 31 away from the shoulder 30 to permit dropping of the 90 crimping mechanism upon the pail cover.

A collar 37 (Fig. 3) carries the circular flange 5 previously mentioned. This is 95 swivelly mounted upon the flanged sleeve 38 of a head 39 which is movably mounted upon the standard 2. The head has a pair of lateral trunnions 40 which enter appropriate holes in the side bars 33. The free extremities of the arms 33 are slotted at 41 (Fig. 1) to receive studs 42 upon the frame 23. The 100 foregoing structure provides a movable mounting for the crimping mechanism upon the handle 33—34, which is capable of being raised and lowered or swung to one side or the other in order to place the crimping 105 mechanism wherever desired.

The operation may now be readily understood. Prior to setting the pail upon the platform 20 the handle 34 is supposed to be 110 swung around approximately 90° from the position shown in Figures 1 and 2 making it possible to set the pail down in a natural

manner, rather than to necessitate sliding the pail in place upon the platform as is the case in machines of this character having a rigid crimping mechanism.

5 Having set the pail P down the handle 34 is swung around to bring the crimping mechanism in position over the cover C. The crimping mechanism is carried by the frame 23 and the entire frame swings upon the 10 rigid standard 21. The cover C is supposed to have been laid in place. The operator then locates the crimping mechanism so that the crimping jaws 10 register with the lugs 13. The crimping mechanism can be spun 15 around because of the swivel mounting of the collar 37 (Fig. 3) upon the flange of the sleeve 38.

The operator next presses the pivoted member 36 which releases the latch 31 from 20 the cylinder 30 permitting dropping of the crimping mechanism upon the cover C. Further pressure in the downward direction upon the handle 34 causes downward movement of the head 39 (Fig. 3) as well as the 25 collar 37 and its attached parts, rocking the arms 9 upon their pivots 11 and causing the jaws 10 to fold the lugs 13 under in the manner disclosed in the foregoing patents. Usually there are eight lugs upon steel covers 30 as herein contemplated, but should the cover happen to have sixteen lugs, as is sometimes the case, the crimping mechanism has only to be raised by means of the handle 34 and given a one-sixteenth turn so that the next 35 set of lugs can be engaged and crimped in the manner explained.

After the crimping operation has been completed the operator raises the handle 34 and permits reengagement of the latch 31 40 with the shoulder 30 so that the crimping mechanism is supported in the suspended and non-operative position. The frame 23 is swung around upon the fixed standard 21, and the pail P is lifted by its bail. The hook 45 25 is brought over in engagement with the frame 23 when it is desired to hold the frame rigid, as for example when moving the apparatus over the floor from place to place.

While the construction and arrangement 50 of the improved apparatus for fastening pail

covers is that of a generally preferred form, obviously modifications and changes may be made without departing from the spirit of the invention or the scope of the claims.

55 I claim:—

1. Apparatus of the character described, comprising a pail-support including a rigid standard, mechanism to crimp the lugs of a cover on a pail set upon the support, said mechanism including a standard and a 60 flanged collar, a frame mounted upon the rigid standard to swing the crimping mechanism across the support and a pail resting thereupon, said frame being of bracket-like construction and terminating in a boss which 65 receives the crimping mechanism-standard for guidance, a handle swingably attached to the frame for operating the crimping mechanism, a head having trunnions applied to the handle thereby to carry the crimping 70 mechanism, said head having a flanged sleeve swivelly supporting said flanged collar, and a latch carried by the handle being engageable with the boss to suspend the handle and crimping mechanism, said handle carrying 75 means to operate and release the latch at times.

2. Apparatus of the character described comprising a pail supporting base, a rigid standard uprising therefrom, an arm having a sleeved end swivelled on said standard and providing a supporting and guiding frame, a fixed collar on said standard upon which the base of said sleeved end is supported for 80 swinging movement of its arm in a horizontal plane transversely of said base, a cover crimping head guided on said frame for movement in a vertical plane toward and from said base, a lever pivoted to said head and fulcruming on said frame for effecting cover crimping operation of said head by its downward movement and vertical head lifting movement by its upward movement, said lever also providing means for effecting 85 bodily swinging movement of the raised crimping head with said swivelled frame in a horizontal plane transversely of the base, with means for latching the head, when elevated, to said frame.
